SOAP DISPENSER HAVING A PIVOTED CUTTER

Walter H. Pumphrey, New York, N. Y., assignor
to Voorhis-Tiebout Company, Inc., Red Hook,
N. Y., a corporation of New York

Application January 1, 1944, Serial No. 516,652

5 Claims. (Cl. 146—61)

1

This invention relates to certain improvements in a soap dispenser for which United States Patent No. 2,191,003 was granted February 20, 1940, to Voorhis-Tiebout Company, Inc., as assignee of Gordon Voorhis of Rhinebeck, New York.

The patented dispenser was designed to use soap cakes of the form disclosed in United States Patent No. 2,011,129, granted August 13, 1935, to the above named company, in which there is a V-shaped groove extending throughout the length of the cake and to about its mid point in depth. The purpose served in grooving the cakes is to save time, labor and plant space in the manufacture of the soap. When grooved cakes are properly stacked, through air passages are formed between the cakes by the grooves which makes it possible to dry the cakes after they are packed in cases for shipment and avoids the necessity of racking; also excessive handling and resulting loss from breakage.

In use in the patented dispenser, the groove of the cake faces outward and a rib is formed on the inner side of the front removable section of the casing, that enters the groove. Theoretically, the rib and groove serve to steady and guide the soap cake but, practically, this action is not required as the cake is snugly fitted in the soap chamber of the dispenser and cannot shift about or become displaced.

Further, in the patented dispenser, the spring of the pressure plate or follower, that advances the soap to the cutter, is attached to the follower in the rear of the soap cake and to prevent the follower plate from being tipped upward at its forward end by the action of the spring, a rear slide and guide are provided to balance the action.

I have found by reversing the soap cake, so that the groove faces rearward, the groove may be utilized to serve the important purpose of enabling the spring of the follower to be positioned therein and attached centrally or substantially so, instead of in the rear of the follower, which equalizes the spring pressure on the follower and does away with the use of the rear slide and guides as well as the above mentioned guide rib on the removable section of the casing.

There is also employed in the patented dispenser, a rotary cutter formed of a number of serrated disks, arranged side by side, in spaced relation, and radially cut and bent up at the edges to provide a series of cutter blades. The only path for the separated soap particles to the delivery opening of the dispenser, is through

2

this very intricate cutter construction, which objectionably obstructs a free flow to the outlet.

To partially remedy this trouble, I reduce the cutter to semi-circular or semi-cylindrical form and oscillate it and to relieve the user of half the work of operating the cutter, I attach the lower end of the follower spring to it, which acts to retract the cutter whenever it is given motion by the user.

10 The conversion of the cutter to a semi-circular oscillating form, gives rise to a number of additional advantages, prominent among which may be mentioned, safety from injury by the cutter, where dispensers are used in schools or like institutions and children of an investigating turn of mind are apt to poke their fingers in the delivery opening from the cutter chamber, while the dispenser is being operated.

Several constructions suitable for carrying my invention into effect are illustrated in the accompanying drawings but I do not wish to be understood as intending to limit myself to either the exact form or details shown, as various changes may be made therein without departing from the 15 spirit and scope of the invention, as outlined in the appended claims.

In the drawings—

Fig. 1 is a view in side elevation, partly in section, of one form of the improved dispenser.

20 Fig. 2 is a cross section on the line s², s², of Fig. 1.

Fig. 3 is a perspective view, on an enlarged scale, of the spring-actuated follower employed in the dispenser.

25 Fig. 4 is a like view of a grooved cake of the material used in the machine.

Fig. 5 is a view similar to Fig. 1, showing a further improved form of the dispenser, and

Fig. 6 is a detail perspective view of the operating assembly in which the active element is indicated by dotted lines.

Referring now to the drawings, 1 indicates the casing of the dispenser which is shaped to provide a chamber 2 for a cake 3 of soap or other material to be dispensed. The cake is vertically disposed in the chamber with its lower end resting on the blades of a cutter 4, which may be of any suitable or well known form. Delivery from the cutter is by way of an opening 5 at the lower end of the dispenser.

30 The cake of soap or other material 3 is provided with a longitudinal groove 6, or its equivalent, which extends throughout its length and to substantially the mid point of its cross sectional area. The front upper portion 7 of the

casing is removable to permit the cake to be entered in the chamber 2 and, as positioned therein, the groove 6 faces rearward. The chamber 2 conforms substantially to the cross sectional shape of the cake and serves to hold and guide it as it is advanced to the cutter.

The advance of the cake to the cutter is effected by a spring-actuated pressure plate or a follower 8, as it will be hereafter termed. The follower, in outline, conforms to the cross sectional form of the grooved cake 3 and is provided with lugs 9, 9, on opposite sides and lugs 10, 10, on the rear end, which run in vertical guide grooves 11, 11 and 12, 12, formed in the walls of the chamber 2, as best shown in Figs. 2 and 3. Thus guided, the follower, resting on top of the cake 3 and exerting pressure thereon, through the action of its spring 13, is prevented from jamming and free to follow the cake downward as it is reduced by the cutter.

In order to equalize the pressure of the spring 13 on and throughout the area of the follower, the spring is positioned in the groove 6, as near the center of the cake as it is practically possible to place it and it is held thus positioned by the rear wall 14 of the casing which is shaped to enter the groove, as best shown in Fig. 2.

The spring is attached at its upper end to an upward extension 15 of the follower, which has a forwardly projecting portion 16 designed to serve as a finger lift for raising the follower when a new cake of material is to be entered in the dispenser. The purpose in attaching the spring above the follower, instead of directly to it, is to maintain the spring sufficiently distended, as the follower approaches the cutter, to exert the required pressure on the cake to insure effective action by the cutter.

At a point just above the cutter, the rear wall of the casing is curved outwardly at 17, as a guide for the spring, which is bent rearward around the curved portion, clear of the groove in the cake, and after passing through an opening 18, in the rear wall, is bent around a reversely curved portion 19 of the casing wall and secured at 20, just above the delivery outlet. As the curved walls 17 and 19 are smoothly finished, they offer no resistance to the action of the spring in expanding and contracting.

The dispenser shown in Figs. 5 and 6, differs from the above described form in two features only, otherwise they are identical.

The features referred to are first, the substitution of an oscillating for a rotary cutter and the utilization of the follower spring for retracting the cutter.

As shown in Fig. 5, the cutter 4^a is designed and arranged to be given a back and forth movement by means of a lever 21 secured exteriorly of the casing on the projecting end 22 of the cutter shaft 23. As the movement of the active surface of the cutter element does not exceed 180 degrees, in oscillation, a cutter of semi-circular or semi-cylindrical form is employed, as shown.

Centrally of the cutter and extending rearward through a slot 24 in the rear curved wall 19 of the casing, an arm 24^a is mounted fast on the shaft 23 and to the projecting end of the arm the lower end of the spring 13 is attached and serves to retract the cutter whenever the lever 21, in the manual operation of the dispenser, is pushed back by the user.

As the operation and the many important advantages of the machine will be apparent from

the foregoing, it will not be necessary to further describe the same.

Having described my invention, I claim:

1. A dispensing machine comprising a casing providing a chamber suitable for containing the material to be dispensed in the form of a longitudinally grooved cake, a manually actuated cutter adapted in operation to reduce the cake to powder, a follower plate resting on the cake and shaped in outline to conform substantially to the cross sectional form of the grooved cake to provide a clear passage in line with the groove, the said plate being provided with an upward extension above the body of the plate, and a continuously acting spring feed operatively positioned to exert constant pressure on the cake to advance it to the cutter by being connected at its upper end above the follower plate to the upward extension thereof, the said spring feed being positioned in the aforesaid groove in such relation to the cake as to equalize its pressure thereon throughout the cross sectional area thereof.

2. A dispensing machine comprising a casing providing a chamber suitable for containing the material to be dispensed in the form of a longitudinally grooved cake, a manually actuated cutter of the oscillating type adapted in operation to reduce the cake to powder and a continuously acting spring feed connected to the cutter to retract the same and arranged to exert constant pressure on the cake to advance it to the cutter, the said spring feed being positioned in the aforesaid groove in such relation to the cake as to equalize its pressure thereon throughout the cross sectional area thereof.

3. A dispensing machine comprising a casing providing a chamber suitable for containing the material to be dispensed in the form of a longitudinally grooved cake, a manually actuated cutter adapted in operation to reduce the cake to powder, the said cutter being of the oscillatory type, the active surface movement of which does not exceed 180 degrees, and a continuously acting spring feed connected to the cutter to retract the same and arranged to exert constant pressure on the cake to advance it to the cutter, the said spring feed being positioned in the aforesaid groove in such relation to the cake as to equalize its pressure thereon throughout the cross sectional area thereof.

4. A dispensing machine comprising a casing providing a chamber suitable for containing the material to be dispensed in the form of a longitudinally grooved cake, a manually actuated cutter adapted in operation to reduce the cake to powder, the said cutter being of the oscillatory type and semi-cylindrical in form, and a continuously acting spring feed suitably attached to retract the cutter and arranged to exert constant pressure on the cake to advance it to the cutter, the said spring feed being positioned in the aforesaid groove in such relation to the cake as to equalize its pressure thereon throughout the cross sectional area thereof.

5. A dispensing machine comprising a casing providing a chamber suitable for containing the material to be dispensed in the form of a longitudinally grooved cake, a manually actuated cutter adapted in operation to reduce the cake to powder, the said cutter being of the oscillatory type, and semi-cylindrical in form, and a continuously acting spring feed attached at its lower end to the active element of the cutter to retract the same and arranged to exert constant

pressure on the cake to advance it to the cutter, the said spring feed being positioned in the aforesaid groove in such relation to the cake as to equalize its pressure thereon throughout the cross sectional area thereof.
